MAURICE GOUDARD AND MARCEL MENNESSON, OF LEVALLOIS-PERRET, FRANCE.

CARBURETER.

1,090,047.

Specification of Letters Patent. Patented Mar. 10, 1914.

Application filed November 26, 1912. Serial No. 733,691.

To all whom it may concern:

Be it known that we, MAURICE GOUDARD and MARCEL MENNESSON, engineers, citizens of the French Republic, residing at 39 Rue 5 Fouquet, Levallois-Perret, Seine, France, have invented certain new and useful Improvements in Carbureters, of which the following is a specification.

This invention relates to improvements in carbureters, and is directed to the general type of construction which is disclosed in the prior U. S. Letters Patent, No. 1,002,700, granted to Jouffret and Renee, Sept. 5, 1911, according to which the carbureter has a single spraying nozzle which is so arranged with respect to the aspirator tube that an action is secured which is similar to, and has the advantages of, the action of carbureters having primary and secondary spraying nozzles. The essential characteristics of the type of construction referred to are the arrangement of the spraying nozzle in a chamber which is distinct from the contracted portion of the aspirator tube, and 25 which is provided with an air inlet distinct from the main air inlet of the carbureter, and the provision of fuel conducting passages between said chamber and the aspirator tube, one of said passages opening into the contracted portion of the aspirator tube and having its utility when the engine is being run at mean or greater speed, and the other passage opening into said tube at a 30 point in advance of the throttle and having its utility when the engine is being run at reduced or low speed.

The principal objects of the present invention are to provide a carbureter of the general type referred to which has especial facility of operation during changes from a low to a higher speed; which embodies an organization of extremely simple and accessible character; which is particularly compact, both its maximum vertical and horizontal dimensions being shorter than that of a known carbureter of the type referred to having an equal capacity; and which avoids the disadvantages caused by the "drowning" of the float in the carbureters ordinarily employed.

The invention consists in certain novel features of construction, combination, and arrangement which will be specifically pointed out as the description proceeds.

An embodiment of the invention is illus-

trated, by way of example, in the accompanying drawings, wherein:—

Figure 1 is a vertical sectional view on the line 1—1 of Fig. 2, showing a carbureter in which the features of the invention are incorporated; and Fig. 2 is a plan view of the same.

Similar characters of reference designate corresponding parts in both of the figures.

The lower part *a* of the body of the carbureter is formed to provide a float chamber and incloses a float *b* which is movable in the direction of the axis of the chamber *a* and is preferably, though not necessarily, in the form of a liquid containing vessel, being open at its upper end so as to receive liquid fuel from the chamber *a*. A fuel inlet connection *a'* is provided at the lower end of the chamber *a* and is controlled by a needle valve *b'* carried by the float *b* and projecting downwardly from the bottom thereof.

The mixing chamber of the carbureter is separated from the float chamber by a partition *a²* which is formed as a cup and projects into the float chamber below the normal level of the liquid therein, such normal level, in the embodiment disclosed, being that of the liquid in the float *b*. The lower portion of the partition *a²* is formed with an offset which provides a chamber *e* in which is arranged the spraying nozzle *c*, the upper end of said nozzle being below the normal fuel level. The partition *a²* is provided with a centrally located upright pipe *d* which projects into the restricted portion of the aspirator tube, and at its lower end communicates with the chamber *e* of the spraying nozzle. The pipe *d* forms one of the connections between the spraying nozzle and the aspirator tube, being the connection which is utilized when the motor is running at mean or greater speed, and is provided with an aperture *f* below the normal fuel level, through which a portion of the fuel passes from the float chamber into the lower portion of the cup-like partition *a²*. The partition *a²* is also provided with a cylindrical sleeve *a³* which extends upwardly and obliquely from the chamber *e* and incloses a tubular member *c'*. The member *c'* extends throughout the length of the sleeve *a³*, its lower end preferably surrounding and being fixed to, the spraying nozzle *c*. The relative diameters of the sleeve *a³* and the member *c'* are such that an intervening

annular passage g is provided, which passage terminates short of the upper end of the member c' , the latter, for this purpose, having its upper portion of enlarged diameter and fitting closely against the inner face of the sleeve a^3 . The passage g communicates at its upper end, through a duct i , with the atmosphere, and at its lower end with the chamber e and also, through orifices l , arranged just above the nozzle c , with the bore h of the member c' .

The member c' provides the second connection between the nozzle c and the aspirator tube, and has its utility for this purpose when the engine is running at low or reduced speed. Accordingly, the upper end of the bore h of the member c' communicates with the upper part a^4 of the aspirator tube at a point suitably in advance of the throttle a^6 , the connections for establishing such communication comprising an annular external groove k in the upper part of the member c' , orifices m formed in the member c' and communicating with said groove, and a duct j also communicating with said groove and leading to the upper portion of the aspirator tube, the said duct j being formed in a web which connects the sleeve a^3 and the aspirator tube a^4 . The efficient discharge area of the orifices m is regulated by a screw c^2 which is threaded into the upper end of the member c' and is disposed axially of said member.

In other respects the carbureter is constructed in any suitable manner, but preferably in the manner shown in the drawings, in which the aspirator tube a^4 is co-axial with the pipe d and projects across the laterally directed main air inlet a^5 , whereby the air drawn through said inlet is forced to pass across the surface of the fuel resting upon the bottom of the cup-like partition a^2 .

When the engine is to be started, the partition a^2 contains a relatively small amount of liquid fuel, and the throttle a^6 is in its position of minimum opening. The engine, at starting, produces a suction through the duct j , which, by reason of the travel of air through the duct i , the passage g , the orifices l , and the bore h of the member c' , causes the drainage of substantially all of the liquid fuel above the nozzle c , the said air and the liquid fuel carried thereby forming an explosive mixture which passes through the duct j into the aspirator tube and thence to the engine. The explosive mixture thus delivered to the aspirator tube is augmented by the addition of a mixture composed of the air drawn in through the main air inlet a^5 and the liquid fuel taken up by said air during its travel across the body of fuel contained in the partition a^2 . As a consequence, the engine is started with certainty and rapidity.

When the engine has been started, as just

explained, the throttle a^6 is opened to a greater or less extent and thereupon a mixture of air and fuel is drawn into the aspirator tube, in known manner, through the pipe d , the air admitted through the duct i traveling through the passage g and mixing with the fuel delivered by the nozzle c . The mixture of air and fuel delivered by the pipe d combines with the air drawn in through the main air inlet a^5 to form an explosive mixture, such air taking up the rest of the fuel, if any there be, that remains in the partition a^2 after the engine has been started.

The carbureter operates in the manner detailed in the preceding paragraph until the throttle is again brought into a position of approximate minimum opening, at which time the suction transmitted through the pipe d diminishes sufficiently to provide for the discharge of a mixture of air and fuel through the duct j as previously described.

It is, of course, obvious that the weight of the float b and the diameter of the fuel inlet a' and of the needle valve b' are so selected that the liquid in the chamber a will be level with the upper end of the float b when the needle valve is closed, and that the supply of liquid in the chamber a is increased when the float, becoming lighter by reason of the drainage of its contained liquid, rises and opens the needle valve. The liquid thus admitted into the chamber a ultimately flows over the upper edge of the float, and causes the latter to move downwardly and close the needle valve. Suitable abutments a^6 are fixed in the chamber a to limit the upward movement of the float and to insure the reliability of its action.

Having fully described our invention, we claim:

1. A carbureter having a float chamber, an aspirator tube located above the float chamber, a throttle valve in the aspirator tube, a main air inlet communicating with the aspirator tube, a partition separating the aspirator tube from the float chamber, a spraying nozzle arranged in the float chamber below the liquid level, a chamber for the spraying nozzle, an upright pipe connected to said last named chamber and projecting through the partition into the lower end of the aspirator tube, a second pipe extending upwardly and obliquely from the spraying nozzle, a duct leading from the upper end of said second pipe to the aspirator tube at a point in advance of the throttle valve, and a second air inlet for supplying air to mix with the fuel delivered by the spraying nozzle prior to its passage into the aspirator tube through either of said pipes.

2. A carbureter having a float chamber, an aspirator tube located above the float chamber, a throttle valve in the aspirator tube, a partition separating the aspirator tube from the float chamber, the partition

being of cup-like form and projecting into the float chamber below the normal liquid level thereof, a spraying nozzle arranged in the float chamber below the partition, a 5 chamber for the spraying nozzle, an upright pipe connected to said last named chamber and projecting into the lower end of the aspirator tube, said pipe having an orifice communicating with the cup-like interior of 10 said partition and through which liquid fuel passes into said partition, a main air inlet communicating with the lower end of the aspirator tube, a second pipe leading from the spraying nozzle and connected to the 15 aspirator tube at a point in advance of the throttle valve, and a second air inlet for supplying air to mix with the fuel delivered by the spraying nozzle prior to its passage into the aspirator tube through either of 20 said pipes.

3. A carbureter having a float chamber, an aspirator tube located above the float chamber, a throttle valve in the aspirator tube, a partition separating the aspirator tube from the float chamber, the partition being of cup-like form and projecting into the float chamber below the normal liquid level thereof, a spraying nozzle arranged in the float chamber below the partition, a chamber for the 30 spraying nozzle, an upright pipe connected to said last named chamber and projecting into the lower end of the aspirator tube, said pipe having an orifice communicating with the cup-like interior of said partition and through which liquid fuel passes into 35 said partition, a main air inlet communicating with the lower end of the aspirator tube, a second pipe extending upwardly and obliquely from the spraying nozzle, a duct 40 leading from the upper end of said second pipe to the aspirator tube at a point in advance of the throttle valve, and a second air inlet for supplying air to mix with the fuel delivered by the spraying nozzle prior to its 45 passage into the aspirator tube through either of said pipes.

4. A carbureter having a float chamber, an aspirator tube located above the float chamber, a throttle valve in the aspirator tube, 50 a main air inlet communicating with the aspirator tube, a partition separating the aspirator tube from the float chamber, the partition being of cup-like form and projecting into the float chamber, a spraying 55 nozzle arranged in the float chamber below the partition and below the normal liquid level of said chamber, a chamber for the spraying nozzle, an upright pipe connected to said last named chamber and projecting 60 through the partition into the lower end of the aspirator tube, a second pipe extending upwardly and obliquely from the spraying nozzle, a duct leading from the upper end of said second pipe to the aspirator tube 65 at a point in advance of the throttle valve,

and a second air inlet for supplying air to mix with the fuel delivered by the spraying nozzle prior to its passage into the aspirator tube through either of said pipes.

5. A carbureter having a float chamber, an 70 aspirator tube located above the float chamber, a throttle valve in the aspirator tube, a main air inlet communicating with the aspirator tube, a partition separating the aspirator tube from the float chamber, a spraying nozzle arranged in the float chamber below the liquid level, a chamber for the spraying nozzle, an upright pipe connected to said last named chamber and projecting through the partition into the lower end of the aspirator tube, a sleeve extending upwardly and obliquely from the chamber for the spraying nozzle, a web connecting the upper end of the sleeve and the aspirator tube and having a duct therethrough which 75 communicates with the aspirator tube at a point in advance of the throttle valve, a tubular element confined in the sleeve and extending from the spraying nozzle, the tubular element having orifices in its lower 80 end just above the spraying nozzle, and orifices in its upper end communicating with the duct, the tubular element having near its upper end and below its upper orifices a portion of enlarged diameter fitting closely 85 within the sleeve, the restricted diameter of the tubular element for the remainder of its length providing for an annular passage 90 between said element and the sleeve and which communicates with the chamber for the spraying nozzle, and an air inlet in the sleeve communicating with said annular 95 passage.

6. A carbureter having a float chamber, an aspirator tube located above the float 100 chamber, a throttle valve in the aspirator tube, a partition separating the aspirator tube from the float chamber, the partition being of cup-like form and projecting into the float chamber below the normal liquid 105 level thereof, a spraying nozzle arranged in the float chamber below the partition, a chamber for the spraying nozzle, an upright pipe connected to said last named chamber and projecting into the lower end 110 of the aspirator tube, said pipe having an orifice communicating with the cup-like interior of said partition and through which liquid fuel passes into said partition, a main air inlet communicating with the lower end 115 of the aspirator tube, a sleeve extending upwardly and obliquely from the chamber for the spraying nozzle, a web connecting the upper end of said sleeve and the aspirator tube and having a duct therethrough which 120 communicates with the aspirator tube at a point in advance of the throttle valve, a tubular element confined in the sleeve and extending from the spraying nozzle, the tubular element having orifices in its lower 125 130

4
end just above the spraying nozzle, and orifices in its upper end communicating with the duct, the tubular element having near its upper end and below its upper orifices a portion of enlarged diameter fitting closely within the sleeve, the restricted diameter of the tubular element for the remainder of its length providing for an annular passage between said element and the sleeve and which communicates with the chamber for the spraying nozzle, and an air inlet in the sleeve communicating with said annular passage.

5 7. A carbureter having a float chamber, an aspirator tube located above the float chamber, a throttle valve in the aspirator tube, a main air inlet communicating with the aspirator tube, a partition separating the aspirator tube from the float chamber, the partition being of cup-like form and projecting into the float chamber, a spraying nozzle arranged in the float chamber below the partition and below the normal liquid level of said chamber, a chamber for the spraying nozzle, an upright pipe connected to said last named chamber and projecting through the partition into the lower end of the aspirator tube, a sleeve extending upwardly and obliquely from the chamber for the spraying nozzle, a web connecting the upper end of said sleeve and the aspirator tube and having a duct therethrough which communicates with the aspirator tube at a point in advance of the throttle valve, a tubular element confined in the sleeve and extending from the spraying nozzle, the tubular element having orifices in its lower end just above the spraying nozzle, and orifices in its upper end communicating with the duct, the tubular element having near its upper end and below its upper orifices a portion of enlarged diameter fitting closely within the sleeve, the restricted diameter of the tubular element for the remainder of its length providing for an annular passage between said element and the sleeve and which communicates with the chamber for the spraying nozzle, and an air inlet in the sleeve communicating with said annular passage.

10 8. A carbureter having a float chamber provided with a fuel inlet in its bottom, a cup-shaped float arranged in said chamber and having its bottom provided with a needle valve to control said fuel inlet, an aspirator tube located above the float chamber, a throttle valve in the aspirator tube, a main air inlet communicating with the aspirator tube, a partition separating the aspirator tube from the float chamber, the partition being of cup-like form and projecting into the confines of the float, a spraying nozzle arranged within the float below the partition and below the normal liquid level, a chamber for the spraying

15 nozzle, an upright pipe projecting from said chamber through the partition into the lower end of the aspirator tube, a second pipe extending upwardly and obliquely from the spraying nozzle, a duct leading 70 from the upper end of said second pipe to the aspirator tube at a point in advance of the throttle valve, and a second air inlet for supplying air to mix with the fuel delivered by the spraying nozzle prior to 75 its passage into the aspirator tube through either of said pipes.

20 9. A carbureter having a float chamber provided with a fuel inlet in its bottom, a cup-shaped float arranged in said chamber 80 and having its bottom provided with a needle valve to control said fuel inlet, an aspirator tube located above the float chamber, a throttle valve in the aspirator tube, a main air inlet communicating with the 85 lower end of the aspirator tube, a partition separating the aspirator tube from the float chamber, the partition being of cup-like form and projecting into the confines of the float, a spraying nozzle arranged within the float below the partition and below the normal liquid level, a chamber for the spraying nozzle, an upright pipe projecting from said chamber through the partition into the lower end of the aspirator tube, said pipe having an orifice 90 communicating with the cup-like interior of said partition and through which liquid fuel passes into said partition, a second pipe extending upwardly and obliquely 95 from the spraying nozzle, a duct leading from the upper end of said second pipe to the aspirator tube at a point in advance of the throttle valve, and a second air inlet 100 for supplying air to mix with the fuel delivered by the spraying nozzle prior to its passage into the aspirator tube through either of said pipes.

25 10. A carbureter having a float chamber provided with a fuel inlet in its bottom, a cup-shaped float arranged in said chamber 110 and having its bottom provided with a needle valve to control said fuel inlet, an aspirator tube located above the float chamber, a throttle valve in the aspirator tube, a main air inlet communicating with the lower end of the aspirator tube, a partition separating the aspirator tube from the float chamber, the partition being of cup-like form and projecting into the confines of the 115 float, a spraying nozzle arranged within the float below the partition and below the normal liquid level, a chamber for the spraying nozzle, an upright pipe projecting from said chamber through the partition into the lower end of the aspirator tube, said pipe having an orifice 120 communicating with the cup-like interior of said partition and through which liquid fuel passes into said partition, a sleeve extending upwardly and 125

30 65

obliquely from the chamber for the spraying nozzle, a web connecting the upper end of said sleeve and the aspirator tube and having a duct therethrough which communicates with the aspirator tube at a point in advance of the throttle valve, a tubular element confined in the sleeve and extending from the spraying nozzle, the tubular element having orifices in its lower end just above the spraying nozzle, and orifices in its upper end communicating with the duct, the tubular element having near its upper end and below its upper orifices a portion of enlarged diameter fitting closely within the sleeve, the restricted diameter of the

tubular element for the remainder of its length providing for an annular passage between said element and the sleeve and which communicates with the chamber for the spraying nozzle, and an air inlet in the sleeve communicating with said annular passage.

In testimony whereof we have hereunto set our hands in presence of two subscribing witnesses.
